(57) **CLAIM**

The ornamental design for an LED lighting fixture, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a perspective view of an LED lighting fixture, showing our new design;

FIG. 2 is a top view of the LED lighting fixture of FIG. 1; FIG. 3 is a bottom view of the LED lighting fixture of FIG. 1;

FIG. 4 is a right side elevational view of the LED lighting fixture of FIG. 1;

FIG. 5 is a left side elevational view of the LED lighting fixture of FIG. 1;

FIG. 6 is a left end elevational view of the LED lighting fixture of FIG. 1; and,

FIG. 7 is a right end elevational view of the LED lighting fixture of FIG. 1.

The portions of the LED lighting fixture shown in broken lines form no part of the claimed design.
